UNITED STATES PATENT OFFICE.

ARCHIBALD K. ALLEN, OF SEATTLE, WASHINGTON.

DESIGN FOR AN AUTOMOBILE-TIRE.

45,083.

Specification for Design.

Patented Dec. 30, 1913.

Application filed July 22, 1913. Serial No. 780,582. Term of patent 14 years.

To all whom it may concern:

Be it known that I, ARCHIBALD K. ALLEN, a citizen of the United States, residing at the city of Seattle, in the county of King and State of Washington, have invented a new, original, and ornamental Design for Automobile-Tires, of which the following is a specification, reference being had to the accompanying drawing, forming part thereof.

Figure 1 is a plan view, and Fig. 2 is a fragmentary side view.

I claim:

The ornamental design for an automobile tire, as shown.

ARCHIBALD K. ALLEN.

Witnesses:

VIVIANNE ADAMS KELLOGG,
HARRISON M. BROOKS.
